Friedrich LLP(57) **CLAIM**We claim the ornamental design for a light, as shown and
described.

DESCRIPTION

FIG. 1 is a perspective view of light embodying the invention;

FIG. 2 is a front view of the light of FIG. 1;

FIG. 3 is a rear view of the light of FIG. 1;

FIG. 4 is a left side view of the light of FIG. 1;

FIG. 5 is a right side view of the light of FIG. 1;

FIG. 6 is a top view of the light of FIG. 1; and,

FIG. 7 is a bottom view of the light of FIG. 1.

The elements shown in broken lines are included for the
purpose of illustrating environment and form no part of the
claimed design.**1 Claim, 7 Drawing Sheets**# US D816,252 S
